(57) **CLAIM**

The ornamental design for a towel hanger, as shown and described.

DESCRIPTION

FIG. 1 is a perspective view of the towel hanger according to the invention;

FIG. 2 is a top plan view of the towel hanger of FIG. 1;

FIG. 3 is a bottom plan view of the towel hanger of FIG. 1;

FIG. 4 is a left side elevation view of the towel hanger of FIG. 1, with the right side elevation view being identical;

FIG. 5 is a front elevation view of the towel hanger according to the invention;

FIG. 6 is a rear elevation view of the towel hanger of FIG. 1;

FIG. 7 is a cross-sectional view of the towel hanger through line 7-7 shown in FIG. 5;

FIG. 8 is a cross-sectional view of the towel hanger through line 8-8 shown in FIG. 5; and,

FIG. 9 is a perspective view of the towel hanger of FIG. 1, and also showing a towel in broken lines in its intended use position.

The broken lines showing a partial towel are for the purposes of illustrating environment and form no part of the claimed design.
